UNITED STATES PATENT OFFICE.

HERBERT S. MILLS, OF CHICAGO, ILLINOIS.

DESIGN FOR A DIAL-FRAME.

SPECIFICATION forming part of Design No. 32,951, dated July 17, 1900.

Application filed June 7, 1900. Serial No. 19,470. Term of patent 14 years.

To all whom it may concern:

Be it known that I, HERBERT S. MILLS, a citizen of the United States, residing at Chicago, in the county of Cook and State of Illinois, have invented and produced a new and original Design for a Dial-Frame, of which the following is a specification, reference being had to the accompanying drawing, forming part thereof.

As shown in the drawing, the leading or material feature of my design consists of a part A, with a circular inner edge and a polygonal outer edge, a base B, and two draped figures C C, standing upon the base and lean-

ing in opposite directions against supports 15 D D.

Having described my invention, what I claim as new, and desire to secure by Letters Patent, is—

The design for a dial-frame as herein shown 20 and described.

In testimony whereof I have signed my name in the presence of two subscribing witnesses.

HERBERT S. MILLS.
